UNITED STATES PATENT OFFICE.

JESSE HAYSE JOHNSON, OF KANSAS CITY, KANSAS.

SHOE FOR PROTECTING PIANOS.

Application filed April 17, 1926. Serial No. 102,823.

This invention relates to shoes or covers for protecting pianos when moving or handling the same and more particularly to means for protecting the toes of upright pianos.

The object is to provide a simple and inexpensive cover which may be easily and quickly applied to the forward or toe end of the heavy base member employed at either side of ordinary upright pianos and to the lower portion of the usual leg or pedestal for supporting the key-board, such portions being generally subjected to the greatest danger of damage when being passed through doors and windows during the operation of moving the same, as ordinary covers usually employed to protect the piano proper do not extend to these points and offer no protection thereto.

Another object is to provide a protecting cover of this character which will retain its normal shape to be applied in position without the necessity of specially arranging same for the purpose, said cover being, at the same time, formed of flexible material provided with a soft lining where contacting with the highly polished surfaces of the piano, and having no stiff metallic or similar parts to scratch or otherwise mar such surfaces.

A full and complete understanding of the invention may be obtained from a consideration of the following detailed description, taken in connection with the accompanying drawing forming a part of this specification, it being understood that while the drawing shows a practical form of the invention, the latter is not to be confined to strict conformity with the showing thereof, but may be changed or modified, so long as such changes or modifications mark no material departure from the salient features of the invention, as specifically pointed out in the appended claims.

In the drawing, in which similar reference characters designate corresponding parts throughout the several figures:

Figure 1 is a perspective view of a portion of a piano having the improved shoe or protector applied thereto.

Figure 2 is an enlarged view in side elevation, the invention being shown in section.

Figure 3 is a perspective view of the invention removed from the piano.

Figure 4 is a plan view, on a reduced scale, of the blank from which the shoe or protector is formed.

Serious damage is often done to the exposed lower portions of pianos in moving the same from place to place, especially when it is necessary to pass them through doors and windows, either while in the hands of the piano movers or when suspended from a block and fall, and this is particularly true of the aforementioned parts of the piano, for the reason that the usual piano cover, which is open at the bottom, does not protect these parts and is often lifted by the piano movers in order to enable them to grasp the heavy base member or sill for lifting the same and thus further exposing these parts to damage.

The invention is designed to provide separate covers for each side of the ordinary upright piano to be easily and quickly applied to the front ends of the toes and the lower portions of the legs or pedestals, and to be readily secured in position to remain thereon until the moving operations are completed, and to be then as readily detached.

To this end the illustrated embodiment of the invention comprises a flexible casing formed of heavy canvas or duck or other suitable material and cut into the form of the blank illustrated in Figure 4 of the drawing, said blank comprising an intermediate portion to constitute a front wall 1 of the completed shoe, the marginal portions of said blank being integrally joined to said front wall and adapted, when bent at right angles thereto, to constitute side walls 2 which are preferably somewhat less in width than the front wall.

The intermediate portion of said blank which constitutes the front wall is extended at the lower end to comprise a bottom wall 3 which is integrally connected thereto and is of the same width as the front wall, and when the side walls 2 and the bottom wall 3 are bent perpendicularly in the same direction and along the dotted lines of Figure 4, it will be seen that an open pocket or shoe is provided, the side edges of said bottom wall being suitably stitched to the adjacent lower edges 3a of the side walls 2 to retain said pocket or shoe in shape.

The side walls 2 are provided at their lower ends with rearwardly extending

wings or flaps 4, and the exposed marginal edges of all the parts are held and reinforced by binding 5 extending entirely around the same.

5 At the upper ends of the side walls 2 there are provided strings or tapes 6 terminally attached and extending rearwardly so as to allow their free ends to be used in attaching the device in place, and secured 10 to the upper, rear corners of the side flaps or wings 4 are other similar strings or tapes 7 for the same purpose.

The inner faces of the front and side walls as well as the bottom wall and side wings 15 are all lined with a soft felt lining 8 where coming into contact with the highly polished surfaces of the piano, and said lining and the outer canvas casing are held together and the entire device strengthened by suitable rows of stitching 9 which may traverse 20 the faces or walls in any suitable manner and extend diagonally or otherwise.

In applying the device in protecting position on the front end of the toe A of the 25 piano, the bottom wall 3 extends across beneath said toe in advance of the castor C, and the front and side walls cover the end and sides of said toe, with the side wings 4 extending rearwardly along the side faces of 30 the same. The upper portions of the front and side walls extend around the front and side faces of the base portion of the leg or pedestal B and are held to the latter by means of the tapes 6 which are tied around 35 same to prevent the shoe from falling or moving forwardly while the lower portion of the device is held from forward movement by means of the tapes 7 passing across the upper face of the toe A, the two sets of 40 tapes being suitably tied in a manner to permit of the ready removal of the shoe or protector.

From the foregoing it will be seen that a 45 simple and cheaply manufactured device has been provided which may be easily and quickly applied in position to protect the pedestal and toe portions of upright pianos during the operation of moving the same.

What is claimed is:—

1. A shoe for protecting the toes of pianos 50 comprising a flexible casing having a front wall and integral side and bottom walls to receive and partially surround the end of the toe and the base portion of the leg or pedestal of the piano, and means for securing 55 the same in place.

2. A shoe for protecting the toes of pianos comprising a casing cut and sewed to form opposite side walls joined by an integral front wall and adapted to cover and protect the sides and front faces of the toe and the leg or pedestal at each side of an upright piano, a bottom wall integrally joined to the lower edges of the front and side walls and adapted to lie beneath the toe of the 65 piano in advance of the castor, side wings extending rearwardly from the lower portions of the side walls to protect the sides of the toe, strings or tapes connected to said wings to be tied over the toe, and strings 70 or tapes connected to the upper ends of the side walls to be tied around the leg or pedestal.

3. An article of the class described comprising a shoe or casing having a front wall, 75 side walls and a bottom wall all connected together and adapted to cover and protect the toe and pedestal at either side of an upright piano, said side walls being of substantially the same width as the bottom 80 wall and having rearwardly extending side wings at their lower ends to extend along the sides of the toe beyond the pedestal, strings or tapes secured to the upper, rear corners of the side walls to be tied around 85 the pedestal, and strings or tapes secured to the upper rear corners of the side wings to be tied around the toe to secure the shoe or casing in place, said walls and wings having a soft lining to contact with the polished 90 surfaces of the pedestal and toe and also being suitably stitched at intervals to reinforce the same.

In testimony, that I claim the foregoing as my own, I have hereto affixed my signature.

JESSE HAYSE JOHNSON.
